FIG. 1

FIG. 2

FIG. 3

FIG. 4

FIG. 5

FIG. 1 is a top plan view of a box, showing my new design;

FIG. 2 is a front elevational view thereof;

FIG. 3 is a bottom plan view thereof;

FIG. 4 is a rear elevational view thereof; and

FIG. 5 is an end elevational view thereof taken from the right of FIG. 2.

The end not shown is a mirror image of the end shown in FIG. 5.

The dominant features of my design reside in the portions shown in full lines.

I claim:

The ornamental design for a box, as shown and described.
